CLAIM

The ornamental design for a multi-source power adapter for USB port, as shown and described.

DESCRIPTION

FIG. 1 is a perspective view of the multi-source power adapter for USB port according to the present invention.

FIG. 2 is a front view of the multi-source power adapter for USB port of FIG. 1.

FIG. 3 is a rear view of the multi-source power adapter for USB port of FIG. 1.

FIG. 4 is a right side view of the multi-source power adapter for USB port of FIG. 1.

FIG. 5 is a left side view of the multi-source power adapter for USB port of FIG. 1.

FIG. 6 is a top view of the multi-source power adapter for USB port of FIG. 1.

FIG. 7 is a bottom view of the multi-source power adapter for USB port of FIG. 1; and,

FIG. 8 is a left side view of the multi-source power adapter for USB port of FIG. 1 in an alternate orientation.
